UNITED STATES PATENT OFFICE

2,568,856

SOAP CONTAINING HANDLE

Albert E. Hartmann, New York, N. Y.

Application February 7, 1950; Serial No. 142,760

2 Claims. (Cl. 222—390)

1

This invention relates to shaving brushes and more particularly to the type in which the brush is provided with a soap squirting nozzle within the brush, the amount of soap being determined by the amount of pressure on the soap in the soap reservoir.

The object of the invention is to provide improved means for controlling such pressure.

Heretofore it has been proposed to use helical springs to exert such pressure, but in the use of springs it has been found that their inherent resiliency subject them to a final uncontrolled pressure, which when exerted upon the soap contents extrudes too much soap.

The present invention has for its object to provide means which transmit the identical rotation to the piston as is applied to the exterior cap, no more nor no less.

The invention consists in an exterior rotatable cap applied to one end of the sleeve which forms the soap container, and a shaft connected with the cap and rotatable therewith, and which shaft is secured to the piston in the container to rotate it within the container, said shaft consisting of a plurality of spring blades secured to each other at alternate ends, and held in normal collapsed position and capable of being extended under their inherent resiliency thus pulling on the piston to tighten its thread engagement with the sleeve and on the cap to force it against the end of the sleeve.

The invention will be further described, embodiments thereof will be shown in the drawings, and the invention will be finally pointed out in the claims.

In the accompanying drawings,

Fig. 1 is a vertical central section of the improved device, with the shaft collapsed as in normal position;

Fig. 2 is a like section with the shaft extended;

Fig. 3 is a horizontal section on line 3—3 of Fig. 2;

Fig. 4 is a perspective view of the cap closing the end of the sleeve;

Fig. 5 is a horizontal section taken on line 5—5 of Fig. 2; and

Fig. 6 is a section similar to Fig. 2, with the extended shaft made of fused blades.

Similar characters of reference indicate corresponding parts throughout the various views.

Referring to the drawings, the structure shown in general is like the structures shown and described in my applications Serial No. 775,195, filed September 20, 1947, and Serial No. 45,950, filed August 24, 1948.

2

As known, the sleeve 10 is screwthreaded as at 11 shown in section at its interior as at 12, and a member 13 with a soap dispensing nozzle 14 has exterior screwthreads 15 engaging the screwthreaded sleeve 10. A cap 16 has interior screwthreads 16a to engage the screwthreads 15 of the member 13.

The improvement consists in the soap pressing piston 20, which has exterior screwthreads 20a to engage the interior screwthreads of the sleeve 10, and which by rotation moves longitudinally in the sleeve, for expelling soap through the nozzle. The sleeve 10 at its lower open end is closed by a cap 21 enveloping the exterior of the sleeve 10, being formed of a flat disk 22 and flanges 23, and is rotatable on the end of the sleeve.

Disposed between the cap 21 and the piston is a collapsible bladed turning shaft 25 which has one end secured to the piston 20 and the other end to the cap 21. The shaft 25 is composed of a plurality of metal disks 26, secured successively to each other at their perimeters in staggered relationship, each adjacent pair having their juncture alternately at opposite sides of the axis of the shaft. The metal used is such as to be substantially rigid but has an inherent resiliency, to permit an accordion like expansion when the ends are pulled in opposite directions. The diametrical ends of the disks 26 are secured to each other by rivets 27 or the like, as shown in Fig. 3. In place of rivets, the ends may be fused together as at 27a in Fig. 6. The disks there shown have a waist line 28, but may be circular in contour or of other suitable shape. One end of the shaft 25 is secured to the piston 20 and the other end of the shaft 25 is secured to the cap 21, by rivets 30 or the like. The shaft 25 when collapsed takes up very little room as shown in Fig. 1, wherein the blades are in faying relationship and parallel with each other. When the shaft 25 is extended as shown in Fig. 2, it exerts a pull on the piston 20 and forces its screwthreads against the screwthreads of the sleeve forming an air tight seal, which is important, particularly to prevent the passage of the soap in outward direction, and the inlet of air in the other direction, which might cake the soap cream at the screwthreads.

At the same time the expansion of the shaft 25 tends to force the cap 21 against the sleeve 10, and hold the cap 21 against the end of the sleeve 10. This action takes place to almost the collapse or nested position of the shaft 25, and when the shaft 25 is nested it still holds the cap on,

as the shaft 25 is in its normal collapsed position.

To further assist in holding the cap 21 on the sleeve 10, a crown of metal 31 (Fig. 4), having a plurality of resilient peripheral teeth 32, is secured by a rivet 33 or two to the cap 21, and the teeth then engage a circular groove 34 inside of the sleeve in proximity to its end.

The low depth of the closed shaft as shown in Fig. 1, enables a short sleeve 10 to be provided, so that sleeve 10 and cap 16 constituting the entire brush handle, is not larger but smaller than the ordinary brush handle of the common shaving brush now on the market.

The mechanical parts of the improved device provide a direct transfer of rotative force translated to a longitudinal movement of the soap pressing piston, without any after resiliency as is the case with helical springs. A rotation of the cap is instantly conveyed to the rotation of the position. Simultaneously, the piston threads are pressed against the inner sleeve threads forming an air tight seal, and the cap is at all times pressed against the sleeve.

The blades of the shaft are preferably made of stainless spring steel; and the other parts preferably of aluminum or plastic, such as "Tenite," or the like.

The assembly of the piston blade shaft, and cap can be taken out of the sleeve in its entirety, and cleaned, if necessary, or for repairs, if any. The materials used are rust-proof or non-corrosive.

The cap 23 shown as having its rim on the outside of the sleeve, may be arranged to be within the sleeve.

I wish it to be understood that I do not desire to be limited to the exact details of construction shown and described, for obvious modifications will occur to a person skilled in the art.

I claim:

1. In a soap containing handle having an interiorly threaded sleeve for containing the soap, and an exteriorly threaded piston movable in said sleeve on the rotation of the piston, the combination of a cover for the sleeve, and a longitudinal collapsible shaft disposed between the cover and the piston, said shaft consisting of a series of

superposed blades normally in planes at right angles to the longitudinal axis of the sleeve and smaller in length than the inner diameter of the sleeve, said blades being serially joined to each other at their alternate peripheral margins, with one end blade secured to the piston, and the other end blade secured to the cover, all of the intermediate blades extending across said axis, said blades when nested being in parallel planes substantially contacting with each other, and said blades being adapted to be separated from each other on the movement of said piston away from said cover, excepting for their peripheral margins, whereby on the rotation of the cover, the piston is simultaneously rotated by the radial turning movements of the blades, without transposing any rotary force to a longitudinal force, said shaft when extended, having an inherent resiliency to return to its nested position.

2. In a soap containing handle having an interiorly threaded sleeve for containing the soap, and an exteriorly threaded piston movable in said sleeve on the rotation of the piston, the combination of a cover for the sleeve, and a shaft disposed between the cover and piston, said shaft consisting of a series of superposed tensional blades with their alternate perimeters in faying relationship to form a unit of parallel blades, with one end blade secured to the piston and the other end blade secured to the cover, whereby on the rotation of the cover the piston is rotated, and said unit is extended and has an inherent resiliency to press the threads of the piston against the threads of the sleeve, and to press the cap against the sleeve end.
